UNITED STATES PATENT OFFICE.

THOMAS W. CAUDLE, OF DAYTON, TENNESSEE.

LOCKING DEVICE FOR AXLE-NUTS.

937,924.

Specification of Letters Patent.

Patented Oct. 26, 1909.

Application filed February 23, 1909. Serial No. 479,438.

To all whom it may concern:

Be it known that I, THOMAS W. CAUDLE, a citizen of the United States, residing at Dayton, in the county of Rhea and State of Tennessee, have invented a new and useful Locking Device for Axle-Nuts, of which the following is a specification.

The objects of the invention are, generally, the provision in a merchantable form, of a device of the class above specified which shall be inexpensive to manufacture, facile in operation and devoid of complicated parts; specifically, the provisions of a skein of novel and improved form, of a rod designed to be assembled with the said skein for locking a nut thereto, and of novel means for holding the rod in position upon the skein; other and further objects being made manifest hereinafter as the description of the invention progresses.

The invention consists in the novel construction and arrangement of parts hereinafter described, delineated in the accompanying drawings, and particularly pointed out in that portion of this instrument wherein patentable novelty is claimed for certain distinctive and peculiar features of the device, it being understood, that, within the scope of what hereinafter is thus claimed, divers changes in the form, proportion, size and minor details of the structure may be made without departing from the spirit or sacrificing any of the advantages of the invention.

Similar numerals of reference are employed to denote corresponding parts throughout the several figures of the drawings.

In the accompanying drawings Figure 1 shows my invention in vertical longitudinal section; and Fig. 2 is a vertical transverse section on the line *a b* of Fig. 1.

In the accompanying drawings, the numeral 1 denotes the terminal of the axle 45 of a vehicle upon which is mounted a skein

2. The outer end of the skein 2 is closed and is diminished in diameter and threaded as denoted by the numeral 3, this diminution in the diameter of the skein at its outer terminal forming a shoulder 5 against which may abut, a nut 4, threaded as shown to engage the threaded outer end of the skein.

The skein is provided intermediate its ends with the usual shoulder 6 to receive the wheel of the vehicle and at its inner end it 55 is thickened to form a base 7. The base 7 is provided upon its upper surface with a longitudinally disposed upstanding rib 8 and through this rib 8 and through the body of the skein, passes an aperture 9 communicating with the interior of the skein. The inner surface of the skein at its upper portion is provided with a longitudinally disposed channel 10. This channel 10 crosses the aperture 9 and terminates between said 65 aperture and the inner end of the skein, whereby is formed a shoulder 11. At its outer end the channel 10 is reduced in diameter as denoted by the numeral 12, this reduced portion extending outward through 70 the shoulder 5 of the skein. I further provide a rod 13 conforming in cross section to the cross section of the channel 10 and arranged to be slidably mounted therein. This rod 13 is provided with a diminished end 75 14 adapted to enter the opening 12 in the outer end of the skein. The inner face of the nut 4 has an aperture 15 which the diminished end 14 of the rod is adapted to enter and the dimensions of this aperture 80 15 in the nut are such that when the end 14 of the rod is mounted therein, rotation of the nut 4 upon the threaded portion 3 of the skein will be impossible. Rising from the inner end of the rod 13 is a shank 16 which, 85 as shown, may be threaded. This shank 16 passes upward through the aperture 9 in which it is designed to slide, and carries upon its upper terminal a wing nut 18 or like device threaded to engage the shank. 90 Interposed between the wing nut 18 and the skein is a plate 17 having an aperture to receive the threaded shank 16. As shown in Fig. 2, the edges of this plate 17 are downbent to include between them the rib 95 8 which upstands from the skein adjacent the inner end thereof.

In practical operation, supposing the parts to be in the position shown in Fig. 1, the wing nut 18 is rotated, leaving the rod 100 13 free to slide in the channel 10. The wing nut 18 is then drawn inward carrying with it the rod 13 and retracting the diminished end 14 of the rod from the aperture 15 in

the nut 4, whereupon the said nut may be turned and removed from its place.

When it is desired to replace the nut 4, the end 14 of the rod being retracted within 5 the skein, the nut is rotated into position. By means of the wing nut 18 the rod 13 is forced outward in the channel 10 to cause the end 14 of the rod to enter the aperture 15 in the nut it being understood that this 10 aperture 15 in the nut is so placed relative to the opening 12 in the skein that the said openings 15 and 12 may be brought into alinement by the rotation of the nut. When the nut has thus been locked in position the 15 wing nut 18 may be rotated drawing the rod 13 closely against the inner face of the skein. By the foregoing operation the rod is securely held in engagement with the nut and the nut cannot be removed from its position 20 upon the end of the device until the wing nut 18 has been loosened. The plate 17 which is carried by the shank 16 serves to exclude from the aperture 9, sand and dirt which otherwise might impede the operation 25 of the device, and by downturning the edges of the plate to engage the rib 8, the exclusion of dirt from the orifice is made more perfect. The shoulder 11 is so positioned that it will limit the inward 30 movement of the rod 13 and prevent the threads upon the shank 16 from being damaged by contact with the walls of the aperture 9 as the rod is slid inward.

Having thus described my invention what 35 I claim as new and desire to protect by Letters Patent is.

1. In a device of the class described, a skein having an opening in its top adjacent its inner end; a nut to engage the outer end 40 of the skein; a rod slidably mounted in the skein and arranged to engage the nut against rotation, the rod being provided at its inner end with a shank to slide in the opening in the top of the skein; and means 45 carried by the upper terminal of the shank for clamping the rod to the skein.

2. In a device of the class described, a skein having an opening in its top adjacent its inner end, a nut to engage the outer end 50 of the skein; a rod slidably mounted in the skein and arranged to engage the nut against rotation, the rod being provided at its inner end with a shank to slide in the opening in the top of the skein; a plate carried 55 by the shank of the rod and arranged to cover the opening in the top of the skein; and means carried by the upper terminal of the shank for clamping the rod to the skein.

3. In a device of the class described, a skein having an opening in its top adjacent its inner end, and provided on its inner face 60 with a longitudinally disposed channel terminating between the opening and the inner

end of the skein to form a shoulder in the skein; a nut to engage the outer end of the skein; a rod slidably mounted in the channel and arranged to engage the nut against rotation, the rod being provided at its inner end with a threaded shank to slide in the opening in the top of the skein; and a nut 70 to engage the upper end of the shank; the shoulder being positioned to limit the inward movement of the rod and to hold the threaded shank from contact with the skein.

4. In a device of the class described, a skein having an opening in its top adjacent its inner end and provided with an opening in its outer end eccentric with respect to the axis of the skein; a nut to engage the outer end of the skein and provided upon its inner face with an aperture arranged to be brought into alinement with the opening in the outer end of the skein; and a rod slidably mounted within the skein and having its outer terminal arranged to enter in the opening in the outer end of the skein and to enter the aperture in the nut; the rod being provided with a shank to extend through the opening in the top of the skein and to slide therein.

5. In a device of the class described, a skein having an opening in its top adjacent its inner end and provided with an opening in its outer end eccentric with respect to the axis of the skein; a nut to engage the outer end of the skein and provided upon its inner face with an aperture arranged to be brought into alinement with the opening in the outer end of the skein; a rod slidably mounted within the skein and having its outer end arranged to enter the opening in the outer end of the skein and to enter the aperture in the nut, the rod being provided with a shank to extend through the opening in the top of the skein and to slide therein; a plate carried by the shank and positioned to cover the opening in the top of the skein; and means carried by the upper terminal of the skein for clamping the rod to the skein.

6. In a device of the class described, a skein having a longitudinally disposed rib at its top adjacent its inner end, and provided with an opening through said rib to communicate with the interior of the skein, and provided with an opening at its outer end eccentric with respect to the axis of the skein; a nut to engage the outer end of the skein and provided upon its inner face with an aperture arranged to be brought into alinement with the opening in the outer end of the skein; a rod slidably mounted within the skein and having its outer terminal arranged to enter the opening in the outer end of the skein and to enter the aperture in the nut; the rod being provided with a shank 125 to extend through the opening in the top

of the skein and to slide therein; a plate carried by the shank and positioned to cover the opening in the top of the skein, the edges of the plate being downbent to engage the rib; and means carried by the upper terminal of the shank for clamping the rod to the skein.

In testimony that I claim the foregoing as my own, I have hereto affixed my signature in the presence of two witnesses.
